US0D1072431S

(12) **United States Design Patent** (10) **Patent No.:** **US D1,072,431 S**
(45) **Date of Patent:** **** Apr. 29, 2025**

(54) **BOOT**

(71) Applicant: **Hero GmbH & Co. KG**, Mainburg (DE)

(72) Inventor: **Matthias Barsch**, Bietigheim-Bissingen (DE)

(73) Assignee: **Hero GmbH & Co. KG**, Mainburg (DE)

(**) Term: **15 Years**

(21) Appl. No.: **29/869,998**

(22) Filed: **Jan. 13, 2023**

(30) **Foreign Application Priority Data**

Jul. 14, 2022 (WO) WIPO118381

(51) **LOC (15) Cl.** **02-04**

(52) **U.S. Cl.**

USPC **D2/912; D2/957**

(58) **Field of Classification Search**

USPC D2/896-900, 902, 909-912, 920, 943, D2/946, 951, 957, 969, 970, 974

CPC A43B 23/07; A43B 3/16; A43B 5/002; A43B 5/003; A43B 5/00

See application file for complete search history.

(57) **CLAIM**

The ornamental design for a boot as shown and described.

DESCRIPTION

FIG. 1 is a left view of a boot showing my new design; FIG. 2 is a back view thereof;

FIG. 3 is a right side view thereof;

FIG. 4 is a bottom view thereof;

FIG. 5 is a front view thereof;

FIG. 6 is a perspective view of thereof;

FIG. 7 is another perspective view thereof; and,

FIG. 8 is a top view thereof.

1 Claim, 8 Drawing Sheets
